A. SVED

INCANDESCENT ELECTRIC LAMP

Filed Feb. 21, 1927

FIG. 1

INVENTOR.
Alexander Sved

UNITED STATES PATENT OFFICE.

ALEXANDER SVED, OF NEW YORK, N. Y.

INCANDESCENT ELECTRIC LAMP.

Application filed February 21, 1927. Serial No. 169,842.

My invention relates to incandescent electric lamps and more particularly to lamps having refractory filaments, operated in a vacuum or in the atmosphere of any inert gas or vapor.

In my application for Letters Patent for a method of producing high temperatures at a point (application filed simultaneously with this one), I have disclosed a heat and light concentrating unit which in this invention is used to increase the efficiency of incandescent electric lamps.

My present invention comprises certain improvements whereby the main incandescent body is not operated electrically, thus making possible the use of such materials for illuminating purposes which in themselves are very poor conductors of electricity, or conduct electricity only under certain conditions as for example thorium with 1% ceria. The filament which heretofore was the sole illuminant is used in my invention to give initial light, and to supply heat to the main illuminating body, which under the present arrangement may be operated at a very much higher temperature than the filament, thus increasing the efficiency of the lamp more than 100%.

For a better understanding of my invention reference may be had to the accompanying drawing in which for purposes of illustration I have shown one of the many arrangements in which my invention may be embodied. Similar numerals refer to similar parts throughout the several views.

In the particular lamp shown in Figure 1 the main illuminating body 1, spherical in form, is placed in the focus of a bifocal reflector 2. The filament 3, held firmly by the filament supports 4, in the focal path of reflector 2. Here again reference is made to my application for Letters Patent for a method of producing high temperatures at a point (application filed simultaneously with this one). The filament 3 is shaped to conform with the configuration of the focal path of the reflector, and it may be made in any form as for example a wire, or coiled into a close helix. The lead 5 is brought down in a glass tube 6 to be connected to the main illuminant support 7, which is made of a stiff, highly refractory material. The

joint between lead 5 and support 7 is preferably fused into glass tube 6. Lead 8 makes electrical connection with the filament and lead 5.

The bifocal reflector 2, highly polished, may be made of any material of good heat and light reflecting properties, is supported by glass rods 9 with the aid of clamps 10 riveted to the reflector. Through one of the clamps 10, lead 11 is connected to the reflector so that the electrical connection may be completed by lead 12 to the filament 3. This form of electrical connection is of great value, on account of the additional support given to the filament by the magnetic pull of the electrified reflector, for the sagging of the filament at high temperatures is a common occurrence. If however it is desirable, the lead 11 may be carried directly to the filament.

Glass tube 13 is the usual support for the internal structure of the lamp, carrying the leads 5 and 11 and the exhaust tube 14. This whole structure as described and shown by the drawing is enclosed in a transparent or semi-transparent envelop 15, made in any desirable form preferably of glass, to which the screw cap 16 is attached in the usual manner by cement.

Figure 2 is a transverse section of the internal structure of the lamp between the filament 3 and the refractory substance 1, looking in the direction of the filament.

In order to prevent the oxidation of the reflector if it is made of metal, and that of the filament it is desirable that the whole system be operated in a vacuum or preferably in an inert gas such as nitrogen, helium, argon, etc.

To properly understand the mode of operation of this lamp the following considerations are offered. It is a known fact that in incandescent lamps, even in the most efficient ones, only a comparatively small amount of the electrical energy supplied to the filament is available as light. The greatest portion of the energy supplied is given off as heat by convection and radiation. The filament offers resistance to the flow of the electric current, and in overcoming this resistance a certain amount of energy is expended in the filament when the current is

caused to flow. The energy thus expended manifests itself as heat. The filament, made invariably in an attenuated form, is so designed that its radiating surface is not sufficient to give off the heat thus developed at ordinary temperatures. As a result, the filament is overheated and if made of the proper material it becomes incandescent and gives off light. Since the rate of radiation depends upon the temperature, the working temperature of the filament is reached when the energy given off by it is equal to that which is supplied to it by the current.

Guillaume's law states that the light given off varies as the twelfth power of the absolute temperature of the source. From this it is clear, that for maximum efficiency the filament should be worked at the highest possible temperature.

But at this time filaments are operated at such high temperatures that no further gain in efficiency seems possible, for while it may be possible to raise the temperature of the filament the life of the lamp will be greatly reduced.

In my present invention this difficulty is overcome by employing a main illuminating body which could be worked at a much higher temperature than any filament, thus increasing the efficiency of the lamp materially. This is made possible by the fact that the main illuminating body is entirely out of the electrical circuit, and it is used in the spherical form in mass, instead of the attenuated form of a delicate wire. Furthermore the main illuminating body may be made of any material which becomes incandescent at a much lower temperature, than the material used for filament.

In the common form of incandescent lamps some of the light and heat which is directed toward the sockets is absorbed and wasted in heating up the fixture, and in addition shades are used to direct the light away from the sockets. Some of the light then becomes available as reflected light. In my invention the light and heat which is directed toward the sockets is utilized to heat the main illuminating body in the following manner. In the lamp depicted in the drawing, when the filament is working heat is radiated and light is emitted in all directions from the filament. The reflector is so designed that exactly one half of the light and radiant energy given off is available for illuminating purposes, while the other half becomes incident upon the reflector. Neglecting losses due to the heating of the reflector, all the light and radiant energy reflected from the reflector will be concentrated on the main illuminating body at the focus. Here special attention is requested to the unusual design of the reflector which makes this condition possible.

(Here again, reference is made to applica-

tion filed simultaneously with this one.) If desired the reflector may be so designed that more than one half of the energy supplied to the filament will be available for use at the focus.

Radiant energy in itself is cold and heat is manifest only when there is something to receive it. The main illuminating body receives the energy, therefore it becomes heated.

The temperature attained at the focus depends upon the mass and the specific heat of the material used as a main illuminating body, and also upon the rate at which it is capable of giving off heat. The proper proportioning of the size of the main illuminating body therefore is of the utmost importance.

To form a conception of the size of the main illuminating body let us assume merely as an illustration, that in a 40 watt lamp a tungsten filament and a tungsten main illuminating body are used. According to Langmuir tungsten gives off 441 candle power per square millimeter, and drawn tungsten filaments consume 1.15 watts per candle power, although higher efficiency has been obtained in nitrogen filled lamps. Therefore the lamp produces 34.8 candle powers; and the radiating area of the filament from these figures is roughly 79 square millimeters. Since in this particular lamp only half the radiations are available at the focus, the radiating surface area of the main illuminating body should be just one half of the total radiating area of the filament (39.5 square millimeters), in order to give off the energy at the same rate and temperature as it is supplied to it by the filament. It has been stated that the shape of the main illuminant is spherical. A sphere with 39.5 square millimeters radiating surface has a diameter of 3.4 millimeters roughly.

If the diameter of the sphere is slightly reduced its radiating area becomes smaller, and in order to give off the heat as fast as it is supplied to it, the main illuminating body must assume a higher temperature than the filament. At a higher temperature the efficiency is greatly increased.

The melting point of tungsten according to Langmuir is 3267 degrees centigrade, and the working temperature of the filament is 2150 degrees centigrade (in nitrogen filled lamps higher, but the same reasoning applies). The main illuminating body being in the mass, and not in the fine wire form, can safely be heated 300 degrees centigrade higher than the filament. An increase of 300 degrees centigrade in temperature will give about 4.4 times the amount of light than the half filament, or 2.2 times as much as the whole filament. Considering that one half the light given off by the filament is avail-

able for illumination, the total amount of light available is approximately $\frac{5}{2}$ (five halves) that given off by the whole filament.

5 Accounting for losses due to heating of the reflector and due to the reduction of the radiating area of the main illuminating body, instead of 150% increase in efficiency, we may only expect 100%.

10 In this demonstration it was shown that in vacuum lamps 100% increase in efficiency may easily be obtained. The same increase may be obtained in nitrogen lamps or any other lamps, provided the same material is used for both the filament and the main illuminating body. But by this method we are not limited in the selection of the material for the main illuminating body to good electrical conductors. Therefore any 15 material which becomes incandescent when heated may be used. Furthermore we may select a material which becomes incandescent at a much lower temperature than the filament, as for example thoria with 1% ceria, which at the same time may withstand an 20 increase of 500 to 600 degrees centigrade, thus increasing the efficiency 200 or 300%.

In these lamps several seconds elapse before full illuminating power is reached, and 25 depending upon the design and materials used the pick up varies between 5 and 8 seconds, but it must be borne in mind that immediate light is given off by the half filament.

30 35 In order to reduce the heating effect on the reflector its convex surface may be roughened so that it may give off the absorbed heat with greater facility.

What I claim is new and desire to obtain 40 by Letters Patent of the United States is:

1. An incandescent electric lamp comprising a sealed bulb; a highly polished metal reflector, formed by revolving a bifocal segment about an axis at an angle to a line passing through the two foci, the said axis passing through one of the foci; a refractory metal filament placed exactly into and shaped to conform with the configuration of the focal path of the reflector; and a mass 45 of refractory substance of proper dimensions placed at the common focus of the said reflector.

2. An incandescent electric lamp comprising a sealed bulb; a highly polished metal reflector, formed by revolving a bifocal segment about an axis at an angle to a line passing through the two foci, the said axis passing through one of the foci; a refractory metal filament placed exactly into and shaped to 50 conform with the configuration of the focal path of the said reflector, to give initial light and to supply heat to a mass of refractory substance of proper dimensions, placed at the common focus of the reflector.

3. An incandescent electric lamp comprising

ing a sealed bulb; a highly polished metal reflector, formed by revolving a bifocal segment about an axis at an angle to a line passing through the two foci, said axis passing through one of the foci; a refractory filament placed exactly into and shaped to conform with the configuration of the focal path of the reflector; and a mass of refractory substance of proper dimensions which is the main illuminating element of 70 the lamp, placed at the common focus of 75 the said reflector.

4. An incandescent electric lamp comprising a sealed bulb, a highly polished metal reflector, formed by revolving a bifocal segment about an axis at an angle to a line passing through the two foci, said axis passing through one of the foci; a refractory metal filament placed exactly into and shaped to 80 conform with the configuration of the focal path of the reflector; and a mass of refractory substance of proper dimensions placed at the common focus of the reflector, which 85 can be worked at a higher temperature than the filament. 90

5. An incandescent electric lamp, comprising a highly polished metal reflector, formed by revolving a bifocal segment about an axis at an angle to a line passing through the two foci, said axis passing through one of the foci; a refractory metal filament placed exactly into and shaped to conform with the configuration of the focal path of the reflector; and a mass of refractory substance of proper dimensions placed at the common focus of the reflector, which 95 can be worked at a higher temperature than the filament. 100

6. An incandescent electric lamp comprising a sealed bulb, an electrified metal reflector, formed by revolving a bifocal segment about an axis at an angle to a line passing through the two foci, said axis passing through one of the foci; a refractory metal filament placed exactly into and shaped to 105 conform with the configuration of the focal path of the reflector, and a mass of highly refractory substance of proper dimensions placed at the common focus of the reflector. 110

7. An incandescent electric lamp comprising a sealed bulb, a metal reflector, having a highly polished reflecting surface and a 115 roughened convex surface, formed by revolving a bifocal segment about an axis at an angle to a line passing through the two foci, said axis passing through one of the foci; a refractory metal filament placed exactly into and shaped to 120 conform with the configuration of the focal path of the reflector, and a mass of highly refractory substance of proper dimensions placed at the common focus of the reflector. 125

8. An incandescent electric lamp comprising a sealed bulb; a highly polished metal reflector, formed by revolving a bifocal segment about an axis at an angle to a line pass- 130.

ing through the two foci, said axis passing through one of the foci; a refractory metal filament placed exactly into and shaped to conform with the configuration of the focal path of the reflector, and a mass of highly refractory substance spherical in form, placed at the common focus of the reflector.

9. An incandescent electric lamp comprising a sealed bulb; a highly polished metal reflector, formed by revolving a bifocal segment about an axis at an angle to a line passing through the two foci, said axis passing through one of the foci; a refractory metal filament placed exactly into and shaped to conform with the configuration of the focal path of the reflector, and a mass of highly refractory substance, independent of the electric circuit, placed at the common focus of the reflector.
- 10 10. A means of increasing the efficiency of incandescent electric lamps by a combination of a sealed bulb, a highly polished metal reflector, formed by revolving a bifocal segment about an axis at an angle to a line passing through the two foci, said axis passing

through one of the foci; a refractory metal filament placed exactly into and shaped to conform with the configuration of the focal path of the reflector, and a mass of highly refractory substance placed at the common focus of the reflector.

11. An incandescent electric lamp comprising a sealed bulb; a highly polished metal reflector, formed by revolving a bifocal segment about an axis at an angle to a line 35 passing through the two foci, said axis passing through one of the foci; a refractory metal filament placed exactly into and shaped to conform with the configuration of the focal path of the reflector, and a mass of refractory substance of proper dimensions placed at the common focus of the reflector, which becomes incandescent at a much lower temperature than the working temperature 40 of the filament.

Signed at New York in the county of New York and State of New York this 17th day of February A. D. 1927.

ALEXANDER SVED.
